Primary Examiner — Marissa J Cash*Assistant Examiner* — William B Melliar(74) *Attorney, Agent, or Firm* — Millen White Zelano & Branigan; William Nixon(57) **CLAIM**

The ornamental design for a light device with a solar panel, as shown and described.

DESCRIPTION

FIG. 1 illustrates a top perspective view of the light device with a solar panel according to my new design; FIG. 2 illustrates a front elevational view thereof; FIG. 3 illustrates a rear elevational view thereof; FIG. 4 illustrates a right side elevational view thereof; FIG. 5 illustrates a left side elevational view thereof; FIG. 6 illustrates a top plan view thereof; and, FIG. 7 illustrates a bottom plan view thereof.

The broken lines in the drawings depict portions of the light device with a solar panel that form no part of the claimed design.
